UNITED STATES PATENT OFFICE.

CARL CHRISTEL, OF TAUCHA, NEAR LEIPZIG, GERMANY.

DEVICE FOR CLEANING MATRICES OF TYPE-SETTING AND CASTING MACHINES.

Application filed August 24, 1925, Serial No. 52,123; and in Germany September 6, 1924.

My invention relates to a device for cleaning matrices of type-setting machines, and it is an object of my invention to provide a device of the kind described in which the matrices are cleaned on several sides during a single operation and contact of cleaned faces with uncleansed ones is avoided. It is also an object of my invention to provide means for positively feeding the matrices in the proper position, past the brushes which clean them, and to so construct and arrange said brushes that they give the matrices a good polish and that their life is increased.

It is very important that the matrices should be suitably guided on their way past the brushes. Heretofore the matrices were fed past the brushes by means of conveyer belts. In my device there is provided a feeding disc having pairs of lugs on opposite sides which are adapted to engage projections on the sides of the matrices and thus prevent edging of the matrices in either direction of rotation.

The sharp edges of the matrices cause considerable wear to the brushes, and therefore some of the brushes are made adjustable.

It is not enough to remove the dirt from the matrices; it is also important that the brushes should impart to them a certain degree of polish so that they keep tight during the casting operation and do not stick in the channels of the supply hoppers.

I impart this fine polish by means of brushes the bristles of which are of very thin brass wire. Preferably such bristles are made rather long and the brushes themselves make up for wear, so as to increase their life to the maximum.

A further advantage of my machine resides in that it is possible to repeatedly circulate through the machine the matrices to be cleaned, so that the cleaning operation can be repeated as often as required if the matrices are not in the desired condition after the first circulation.

In the drawings affixed to this specification and forming part thereof a device embodying my invention is illustrated diagrammatically by way of example. In the drawings:

Fig. 1 is an elevation,

Fig. 2 is a plan view, of my device and

Figs. 3 and 4 are sections on the lines A—B

and C—D of Fig. 2, respectively.

Referring now to the drawings *a* is a ver-

tical channel secured on the frame *F* of the device through which the matrices *M* are inserted as they come from the type-setting machine. *g* is a disc secured on a shaft *g'* which is rotatably carried in the frame *F* and *g''* is a crank for rotating said shaft. Obviously other means may be provided for this purpose;

p and *q* are pulleys keyed to the shaft *g'*. The pulley *q* is connected with a pulley *r* by a belt or cord and pulley *r* is keyed on a shaft *s* in the frame *F* and supports a roller *t*. A conveyer belt *b*, to which tension is imparted by a spring actuated roller *b'*, is carried on the roller *t* and a guide roller *u* at the front end of the frame *F*. *c* are lugs on the belt *b*, which belt may be of steel, and *d* are laminated springs which allow only the lowermost matrice from the pile in the channel *a* to pass along with the belt *b*.

e is a horizontal brush extending above and parallel to the belt *b*, *h* is an inclined brush which extends along one side of the belt *b*, and *i* is a strip of emery cloth which extends along its other side.

f is a resilient bridge connecting the conveyor *b* with the surface of the disc *g* where the matrices are engaged by lugs *k* and fed past circular brushes *l* to a second bridge *f'* and an ejector *v* which is rotated from the pulley *p* on the shaft *g'*. The brushes *l* are secured to a steel hoop *o* which is held in the frame *F* at *o'* and *o''*. The brushes are connected to said hoop *o* by screws *n* and the hoop is adjusted by means of a right and left hand screw spindle *w*.

The ejector *v* is arranged at the end of a horizontal passage *m* which extends above and parallel to the belt *b* and is connected with the channel *a* at its front end.

The operation of my improved device is as follows:

The matrices inserted in the channel *a* are successively engaged by the lugs *c* of the belt *b* to which motion is imparted by rotating the crank *g''*, and carried to the disc *g* past the bridge *f*. On their way the matrices are cleaned and polished on the upper face by the brush *e* at one edge by the inclined brush *h* and at the other by the strip *i* to which the matrices are held at some pressure by the brush *h*. Each matrix that has passed the bridge *f* is engaged by a pair of lugs *k* on the disc *g* and carried along with said disc past the brushes *l* which act on the lower faces of the matrices. Finally the

matrices move past the bridge *f* and the ejector *v* to the horizontal passage *m* from which they may be removed or, if it is desired to subject them to further cleaning, 5 they may be returned to the channel *a* and the belt *b*.

I claim:—

1. A device for cleaning matrices of type-setting machines comprising a frame, a 10 channel on said frame for guiding said matrices, a belt of steel at the base of said channel, a shaft carried in said frame and operatively connected with said belt, means for rotating said shaft, a disc on said shaft 15 adapted to receive the matrices, brushes distributed along said belt and said disc and adapted to act on said matrices as they are fed past said brushes, and a channel connected with said disc at one end and said 20 feeding channel at the other.

2. A device for cleaning matrices of type-setting machines, comprising a frame, a channel on said frame, for guiding said matrices, a belt of steel at the base of said 25 channel, a shaft carried in said frame and operatively connected with said belt, means for rotating said shaft, a disc on said shaft adapted to receive the matrices, an inclined brush extending along one edge of said 30 belt, a strip of grinding material extending along its opposite edge, a brush extending over the upper surface of said belt and the matrices on said belt, brushes distributed along said disc and adapted to act on said 35 matrices as they are fed past said brushes, and a channel connected with said disc at one end and said feeding channel at the other.

3. A device for cleaning matrices of type-setting machines, comprising a frame, a channel on said frame for guiding said 40 matrices, a belt of steel at the base of said channel, a shaft carried in said frame and operatively connected with said belt, means for rotating said shaft, a disc on said shaft 45 adapted to receive the matrices, an inclined brush extending along one edge of said belt, a strip of grinding material extending along its opposite edge, a brush extending over the upper surface of said belt and the matrices 50 on said belt, brushes distributed around said disc and adapted to act on said matrices as they are fed past said brushes, means for adjusting said last named brushes, and a channel connected with said disc at one end 55 and with said feeding channel at the other.

4. A device for cleaning matrices of type-setting machines comprising a frame, a channel on said frame for guiding said 60 matrices, a belt of steel at the base of said channel a shaft carried in said frame and operatively connected with said belt, means for rotating said shaft, a disc on said shaft adapted to receive the matrices, lugs for 65 positively engaging said matrices on said belt and said disc, the lugs on said disc being arranged in pairs on opposite sides thereof, brushes distributed along said belt and said disc and adapted to act on said 70 matrices as they are fed past said brushes, and a channel connected with said disc at one end and with said feeding channel at the other.

In testimony whereof I affix my signature.

CARL CHRISTEL.
